DIE CASTING MACHINE

Lucian Ring, Detroit, Mich., assignor to Ring Aluminum Development Company, a corporation of Michigan

Application August 2, 1954, Serial No. 447,279

11 Claims. (Cl. 22—68)

This invention relates generally to pressure casting equipment and refers more particularly to improvements in equipment of the type disclosed in my copending application Serial No. 382,079, filed September 24, 1953, now Patent No. 2,837,792, granted June 10, 1958.

In die casting, certain metals such, for example, as aluminum, aluminum alloys and metals having similar characteristics, it has been the practice to ladle the required amount of molten metal by hand into the pressure chamber of a suitable die casting machine in advance of the plunger and thereafter operate the plunger to inject the molten metal into the die cavity. Hand ladling of the molten casting material into the pressure chamber not only consumed considerable time and, hence, reduced the rate of production of a given machine but, in addition, rendered it difficult to produce uniform castings due to variations in temperature of the molten casting material supplied to the pressure chamber.

In my above identified copending application, the molten casting material is drawn into the pressure chamber by vacuum produced within the pressure chamber in response to return movement of the plunger and this material is subsequently injected into the die cavity of the machine by the plunger as the latter is moved on its pressure stroke within the pressure chamber. This arrangement eliminates the hand ladling operation heretofore considered necessary and renders the machine completely automatic so that the rate of production of the machine is not only substantially increased but, in addition, more uniform castings are obtained.

In die casting apparatus of the type set forth in the preceding paragraph, the quantity of molten material admitted to the pressure chamber by the action of the vacuum produced in the pressure chamber is metered through a supply passage and does not substantially exceed the amount required to fill the die cavity and associated gate. This is accomplished by providing the supply or metering passage with an effective cross sectional area predetermined with respect to the volume of the cavity and the vacuum produced in the pressure chamber. The predetermined cross sectional area of the supply passage must be maintained over long periods of use regardless of the temperature of the molten casting material and regardless of any characteristic this material may possess which tends to corrode or otherwise deteriorate the walls of the supply passage. For example, aluminum and alloys of aluminum have a chemical as well as a physical action on the walls of the supply passage and continued flow of this material through the supply passage has a tendency to increase the size of the latter to such an extent that the amount of molten casting material admitted to the pressure chamber greatly exceeds the requirements.

With the above in view, it is an object of this invention to provide a die casting machine wherein the predetermined cross sectional area of the supply passage is maintained over long periods of use regardless of the temperature of the molten material and regardless of the

2

chemical or physical action of the material on the walls of the supply passage. This feature renders it commercially practical to adopt automatic feeding of such metals as aluminum, alloys of aluminum or metals having similar characteristics in die casting apparatus, especially in instances where the metal is drawn into the pressure chamber by a vacuum previously produced in said chamber.

It is another object of this invention to provide a supply unit wherein the supply passage for metering the flow of molten casting material into the pressure chamber is formed in a removable tip composed of a sintered metal such as tungsten carbide, titanium carbide or zirconium boride and a binder such as cobalt or platinum. These materials are highly resistant to the temperature as well as the physical and chemical action of such molten metals as aluminum or alloys of aluminum.

The foregoing as well as other objects will be made more apparent as this description proceeds especially when considered in connection with the accompanying drawings, wherein

Figure 16 is an enlarged sectional view of a part of the feeding means for molten casting material.

In Figure 1 of the drawing, the numeral 20 designates a typical die structure having a stationary part 21 and a movable part 22. The part 21 is suitably fixed to a frame member 23 and the part 22 is supported at the outer side of the part 21 for movement toward and away from the latter part. The adjacent surfaces of the die parts are fashioned to form a cavity 24 in the closed position of the die and to provide a passage or gate 25 leading into the cavity 24.

The part 22 is secured to the inner end of an annular housing 26 having the outer end mounted on a slide 27. The slide 27 is mounted on guide bars 28 having their inner ends secured to the frame member 23. Any suitable means not shown herein may be used for moving the slide 27 in opposite directions along the guides 28 to open and close the die 20.

Mounted within the housing 26 is an ejector plate 29

having pins 30 extending inwardly from the plate 29 through bores formed in the die part 22 and registering with the die cavity 24. The plate 29 is actuated to eject the casting from the die cavity by a rack bar 31 and pinion 32. The bar 31 is secured to the plate 29 at the 5 outer side of the latter and meshes with the pinion 32 which is driven by any suitable means not shown herein.

Molten metal is introduced into the die cavity 24 through an injection or pressure cylinder 33 having an outer end projecting through aligned openings in the frame member 23 and fixed die part 21, as shown in Figures 1 and 4 of the drawings. The outer end of the cylinder 33 is open and communicates with the die cavity 24 through the medium of the passage 25. The open outer end of the cylinder 33 may be closed by a cylindrical plug 34 slidably supported within a bore formed in the movable die part 22 and having an annular tapered seat 35 at the inner end engageable with an annular tapered seat 36 surrounding the open end of the cylinder 33. The angle of taper of the seats 35 and 36 is preferably somewhat different in order to assure a fluid tight seal between said seats when in contact.

As shown in Figure 1 of the drawings, the plug 34 is reduced at its outer end and projects axially through the movable die 22 for connection to the inner end of a lubricant supply tube 37. The tube 37 projects outwardly through an opening in the center of the plate 29 and is slidably supported by a bushing 38. The inner end of the tube 37 communicates with fluid passages formed in the plug 34 in a manner to lubricate the walls of the bore formed in the die part 22 and the outer end of the tube is connected in any suitable manner to a source of lubricant supply. In this connection, it is to be noted that the bore in the movable die part 22 within which the plug 34 is slidably supported is vented to the atmosphere by a passage 39 formed in the movable die part 22. The purpose of the passage 39 is to prevent a pressure from building up at the outer side of the plug 34 during outward movement of the plug relative to the movable die part 22. In addition, it is to be noted that the outer end of the reduced portion of the plug provides a shoulder 40 which is engageable by the ejector plate 29 as the latter is moved inwardly to eject a casting from the cavity 24. The arrangement is such that the plug 34 is moved axially inwardly into sealing engagement with the open outer end of the cylinder 33 by the ejector plate 29 when the latter is operated to eject a casting from the die cavity 24. In any case the plug 34 closes the outer end of the cylinder 33 when the die is opened and renders it possible to produce a vacuum within the cylinder 33, as will be presently described.

The inner end of the cylinder 33 is supported in a block 41 which is shown in Figure 3 of the drawings as formed with a vertically elongated opening 42 therethrough for receiving the cylinder 33. The lower end of the opening 42 is shaped to provide an extended bearing contact with the adjacent outer surfaces of the cylinder 33 and the latter surfaces are maintained in contact with the block by a set screw 43 threadably supported in the block at the top of the latter in a position to extend into the upper end of the opening 42 and engage the cylinder 33. As shown in Fig. 11, the bottom of the block 41 is slotted or cut away to provide a clearance opening 44 directly opposite an intake port 45 formed in the cylinder 33 at the bottom of the latter. The arrangement is such that the intake port 45 is accessible for connection to a source of molten metal supply which will be more fully hereinafter described.

Mounted within the cylinder 33 is a plunger 46 having a reduced part at the outer end externally threaded for detachable engagement by a head 47 which, as shown in Fig. 4, is dimensioned to slidably engage the inner surface of the cylinder 33. The inner end of the head 47 is spaced from the shoulder 44' formed on the plunger

by the reduced outer end of the latter and rings 45' of sealing material are supported on the reduced outer end of the plunger 46. These rings have a wiping action on the inner surface of the cylinder 33 during movement of the plunger 46 in the cylinder and are clamped in place against the shoulder 44' by the head 47. As shown in Figures 6-8 inclusive of the drawings, the inner end of the plunger 46 is supported by a bearing block 48 having a recess 49 which is open at the top to freely receive the inner end of the plunger 46 and a clamping member 50. The portion of the recess 49 at the outer end of the block 48 is shaped to form a saddle 51 for supporting the inner end of the plunger 46, and the clamping member 50 assumes a position in the recess 49 at the inner end of the plunger 46. An annular enlargement 52 is formed on the inner end of the plunger 46 and abuts a shoulder 53 formed on the bearing block 48 to prevent outward axial displacement of the plunger 46 relative to the bearing block 48. Inward axial displacement of the plunger 46 relative to the bearing block 48 is prevented by the clamping member 50 which is secured in the recess 49 of the bearing block by a stud 53'. Upward displacement of the inner end of the plunger 46 relative to the bearing block 48 is prevented by a rib 54 formed on the outer face of the clamping member 50 in a position to engage the top of the enlargement 52, as shown in Figures 6 and 8 of the drawings. The above construction is such that the inner end of the plunger 46 is readily removably secured to the bearing block 48.

The bearing block 48 also serves as a coupling for connecting the inner end of the plunger 46 to a hydraulic motor 55. The hydraulic motor 55 comprises a cylinder 56 and a piston 57 slidably supported within the cylinder 56. As shown in Figure 1 of the drawings, the outer end of the cylinder 56 is secured to a suitable support 58 and the piston 57 is connected to a rod 59 which projects outwardly through the outer end of the cylinder 56. The outer end of the rod 59 is secured to the bearing block 48 in a manner such that movement of the piston 57 in the cylinder 56 imparts a corresponding movement to the plunger 46.

As shown in Figure 12 of the drawings, the piston 57 is operated by a hydraulic fluid medium contained in a reservoir 60 and circulated by a pump 61. The intake side of the pump 61 is connected to the reservoir 60 by a conduit 62 and the discharge side of the pump is connected to a control valve 63. The valve 63 is, in turn, connected to opposite ends of the cylinder 56 and to the reservoir 60 in a manner such that movement of the valve 63 in opposite directions alternately connects opposite ends of the cylinder 56 to the pump and reservoir. The valve 63 may be and preferably is automatically operated to move the plunger 46 back and forth in the cylinder 33 in accordance with a predetermined timed cycle of operation. The means for automatically operating the valve 63 is not shown herein but may be and preferably is the same as the means disclosed in my copending application Serial No. 382,079.

More particularly, upon completion of a casting in the die 20, the parts of the latter are relatively moved to their open positions and the ejection plate 29 is operated to eject the casting from the die cavity 24. At the same time, the ejection plate 29 engages the plug 34 and moves the same inwardly into sealing relationship with the outer end of the cylinder 33. The valve 63 then operates to connect the outer end of the cylinder 56 to the pressure side of the pump 61 and to connect the inner end of the cylinder 56 to the reservoir 60. Thus the piston 57 is moved in an inward direction in the cylinder 56 to impart a corresponding inward movement to the plunger 46 in the cylinder 33. Since the outer end of the cylinder 33 is closed by the plug 34, inward movement of the plunger 46 produces a vacuum in the cylinder 33 and the resulting suction is communicated to the intake

port 45 when the plunger 46 assumes its retracted position inwardly beyond the intake port 45.

As will be presently described, this suction draws a quantity of molten casting material such, for example, as aluminum or alloys of aluminum upwardly through the port 45 into the cylinder 33 at the outer side of the plunger 46. Upon completion of this operation, the valve 63 again operates to reverse the connections aforesaid to the pump 61 and reservoir 60 to move the plunger 46 outwardly. Initial outward movement of the plunger 46 closes the intake port 45 in the cylinder 33 and continued outward movement of the plunger 46 forces the molten material into the die cavity 24 which has previously been closed. In this connection it will be understood that the ejector plate 29 is moved to its inoperative position in timed relation to closing of the die cavity 24, enabling the plug 34 to be moved outwardly relative to the cylinder 33 by the pressure in the cylinder 33 to its inoperative position wherein it forms in effect one wall of the movable part 22 of the die 20 and wherein it does not obstruct the flow of molten casting material from the cylinder 33 into the die cavity 24.

The vacuum produced within the cylinder 33 upon reTRACTING movement of the plunger 46 is sufficient to draw the amount of molten casting material into the cylinder 33 required to properly fill the die cavity 24 and associated gate or gates 25. The vacuum or the amount of pressure drop produced in the cylinder 33 may be varied by regulating the rate of retraction of the plunger 46 and/or by providing relief areas in the seating surface of either the plug 34 or adjacent end of the cylinder 33 to enable the escape of a limited amount of air into the cylinder 33 as the plunger 46 is moved inwardly relative to this cylinder.

In order to produce satisfactory castings on a high volume production basis with a minimum loss of shutdown time for servicing, it is essential to not only supply the correct amount of molten casting material to the die cavity 24, but to also maintain this predetermined supply uniform over long periods of operation. In accordance with the present invention the quantity of molten casting material supplied to the cylinder 33 is metered with respect to the pressure drop created in the cylinder 33 upon reTRACTING movement of the plunger 46, and with respect to the capacity of the die cavity 24 and associated passage or passages 25. However, this feature alone does not assure satisfactory operation for long periods without servicing especially in instances where the molten casting material employed has a physical as well as a chemical action on the material through which the metering orifice is formed. Such casting materials attack the walls of the orifice and increase the size of the orifice to such an extent that far too great a quantity of molten casting material is supplied to the cylinder 33.

The foregoing is a critical problem in the commercial application of die casting apparatus of the type disclosed herein and this problem is solved by the structure of the unit to be presently described for connecting the intake port 45 in the cylinder 33 to a source of supply 65 for the molten casting material. In detail, the source of supply 65 comprises a container 66 supported in any suitable manner directly below the intake port 45 formed in the pressure cylinder 33 and having the top open to the atmosphere. Positioned between the container 66 and the cylinder 33 is a conducting device 67 for molten casting material housed within the container 66. The device 67 has a block 68 elongated in a vertical direction and fashioned with a supply passage 69 extending therethrough from one end to the other. The bottom portion of the block 68 projects into the container 66 through the open top of the latter and is immersed into the molten casting material. Thus, the atmospheric pressure acting on the top surface of the molten casting material in the container 66 tends to force this material upwardly through the supply passage 69.

The wall of the block 68 forming the top of the passage 69 is tapered outwardly to provide an annular seat 70 for the lower end of a plug 71 which is correspondingly tapered to provide a fluid tight joint with the block 68, and which has a vertically extending metering passage 72 registering with the passage 69. The upper end of the plug 71 projects into a recess 73 formed in the cylinder 33 around the intake port 45, and the passage 72 in the plug also registers with the intake port 45. As shown in Figure 16 the upper end of the plug 71 is fashioned with an annular seat 73 surrounding the corresponding end of the passage 72 and engageable with an annular seat 74 surrounding the intake port 45. The seat 74 is conically shaped and the seat 73 is rounded in cross section to have a continuous line contact with the seat 74. Thus, a fluid tight joint is provided between the seats with a minimum area of contact of the seating surfaces. This is desirable since it resists chilling of the plug 71 by the relatively cool cylinder 33 and also reduces the transfer of heat from the plug 71 to the cylinder 33. The lower end of the plug 71 has an annular seat identical to the seat 73 and the upper end of the plug is tapered so that the plug is not only removably supported on the block 68 but, in addition, is reversible. Hence, should one of the seats 73 become defective, the plug 71 may merely be reversed and, should the plug become otherwise defective, it may be readily replaced. Also, the plug 71 may be quickly interchanged with plugs having metering passages 72 of different cross sectional areas. It follows from the above that the amount of molten material admitted to the cylinder 33 through the intake port 45, for a given pressure drop in the cylinder 33, is controlled by the cross sectional area of the metering passage 72. Hence it is important that the plug 71 withstand the temperatures of the molten material as well as the physical and chemical action of the molten material flowing through the passage 72. In order to accomplish the above results and thereby assure satisfactory as well as uniform operation of the die casting equipment for long periods of use without servicing, the plug 71 is formed of a sintered compound such as tungsten carbide, titanium carbide and zirconium boride containing binders of cobalt or platinum. In fact, the block 68 is also preferably formed of the same material as the plug 71 so that deterioration of the block by the flow of molten casting materials through the passage 69 is prevented. The foregoing materials are examples of materials found highly satisfactory for use in die casting equipment employed to produce castings of such metals as aluminum and aluminum alloys. The sintered materials together with the binders specified above are merely given by way of example and other materials may be employed. As previously stated the important consideration is to form the plug 71 of a material which will enable maintaining the cross sectional area of the metering passage 72 uniform over long periods of use.

In operation, the molten material drawn into the cylinder 33 through the intake port 45 impinges on the wall of the cylinder 33 directly opposite the port 45 and eventually causes severe corrosion of the metal. In order to overcome this objection, a plug 75 is removably secured to the wall of the cylinder 33 directly opposite the intake port 45 by the set screw 43. The plug 75 may be formed of the same material as the plug 71 and, in any case, is readily replaceable.

In the present instance, the block 68 together with the plug 71 is supported for movement toward and away from the cylinder 33. The arrangement is such as to permit readily reversing, replacing and/or interchanging the plug 71. As shown in Fig. 11, the block 68 is secured intermediate its ends to a yoke 76 having arms 77 respectively extending upwardly along opposite sides of the cylinder 33 and, respectively, threadably engageable with the lower ends of rods 78. The rods 78 slidably engage opposite sides of the block 41 and the upper ends

of the rods are reduced to provide annular shoulders 79. The reduced upper ends of the rods extend through openings formed in a cross head 80 at opposite ends of the latter, and bushings 81 are respectively supported by the cross head 80 within the openings to slidably engage the rods 78.

The cross head 80 is normally urged in a downward direction toward stops 82, seated on the shoulders 79, by coil springs 83 respectively surrounding the upper ends of the rods 78. The lower ends of the coil springs 83 engage the cross head 80 and the upper ends of the springs 83 engage adjusting nuts 84 secured to the upper end of the rods 78. The central portion of the cross head 80 between the two rods 78 is connected to the lower end of a piston rod 85 having the upper end connected to a piston 86 which is slidably supported within a vertically extending hydraulic cylinder 87. Any suitable valve controlled means (not shown) may be provided for alternately connecting opposite ends of the cylinder 87 to a reservoir and a source of hydraulic fluid under pressure. The arrangement is such that movement of the cross head 80 in a downward direction by the piston 86, lowers the yoke 76 sufficiently to disengage the plug 71 from the cylinder 33. On the other hand, movement of the cross head 80 upwardly by the piston 86, raises the yoke 76 and engages the plug 71 with the cylinder 33. In this connection attention is called to the fact that upward movement of the plug 71 into engagement with the cylinder 33 is effected through the coil springs 83 with the result that said springs absorb the shock of engagement of the plug 71 with the cylinder 33 and prevent damage to the seating surfaces on the plug and cylinder.

In order to avoid overheating the cylinder 33 and plunger 46 by the molten metal during the ejecting operation, provision is made herein for cooling the aforesaid parts. As shown in Figures 4, 5, 9 and 10 of the drawings, the outer end of the cylinder 33 is fashioned to provide a series of passages 88. The passages 88 extend in the general direction of length of the cylinder 33, but are inclined with respect to the cylinder axis to such an extent that the ends of adjacent passages communicate with one another and provide in effect a single circuitous passage. Water or some other cooling medium is circulated through the passages and for accomplishing this result intake and outlet conduits 89 and 90 are respectively connected to opposite ends of the circuitous passage formed by the passages 88. In addition to the above cooling arrangement, the cylinder 33 has diametrically opposed bores 91 extending axially outwardly from the inner end of the cylinder and connected to outlet conduits 92, as shown in Figure 4 of the drawings. Extending axially into each of the bores 91 from the inner end of the cylinder 33 is a tube 93 having a diameter substantially less than the diameter of the bores 91 to provide a jacket for a cooling medium within the bores 91. The inner ends of the tubes 93 are respectively connected to intake conduits 94 which in turn communicate with a source of cooling medium supply, not shown herein. Thus, it will be seen that the cylinder 33 is effectively cooled and is maintained at a more or less uniform temperature throughout the operation of the apparatus.

As shown in Figures 2, 4, 6 and 15 of the drawings the plunger 46 has a bore 95 which extends axially of the plunger from the inner end of the latter and is divided into two communicating passages 96 by a partition 97. Referring now to Figure 2 of the drawings, it will be noted that one passage 96 communicates with an intake conduit 98 for cooling medium under pressure, and the other passage 96 communicates with an outlet conduit 99 for the cooling medium. Consequently, the cooling medium is circulated axially of the plunger 46 and the latter is also maintained at a substantially uniform temperature during the casting operation.

Provision is also made herein for lubricating the inner surface of the cylinder 33 during operation of the plunger 46. For accomplishing this result, the plunger 46 is formed with an axially extending lubricant passage 100. The inner end of the passage 100 is connected to a source of lubricant supply by a conduit 102 and the outer end of the passage communicates with the interior of the cylinder 33 at the inner side of the head 47 on the plunger 46 through ports 103.

In the present instance, the lubricant supply conduit 102 is connected to a lubricant supply cylinder 104 through a control valve 105 and a regulating valve 106 by a conduit 107, as shown in Figure 14 of the drawings. The cylinder 104 contains lubricant under pressure so that opening of the valve 105 causes lubricant to flow into the cylinder 33 through the passage 100 in the plunger 46 at a rate depending upon the adjustment of the valve 106. The valve 105 is operated to supply lubricant to the cylinder 33 each time the die 20 is closed and is actuated by a roller 108 mounted on the slide 27. If desired, the lubricant supply tube 37 for the closure plug 34 may also be connected to the conduit 107 so that a supply of lubricant is introduced into the bore in the die part 22 each time the die is closed.

What I claim as my invention is:

1. In a pressure casting apparatus, a mold cavity, a pressure cylinder having a discharge opening for molten casting material communicating with the cavity and having an intake opening for molten casting material spaced inwardly from said discharge opening axially of said cylinder, a plunger movable in said pressure cylinder in an outward direction outwardly beyond said intake opening to inject molten casting material into said cavity and movable in an inward direction to a retracted position inwardly beyond the intake opening, means for closing said discharge opening upon initial inward movement of said plunger toward its retracted position to provide a vacuum in said pressure cylinder produced solely by the inward movement of said plunger and sufficient to draw molten casting material into said cylinder through said intake opening when the latter is uncovered by movement of said plunger to its retracted position, means for admitting molten casting material to said pressure cylinder including a part having a passage communicating with said intake opening and of a cross-sectional area predetermined to admit a metered amount of molten casting material to said pressure cylinder in response to the vacuum produced in said cylinder by said plunger, said part being formed of a material characterized in that it withstands the temperature of the molten casting material without deterioration and is not affected by the physical and chemical action of the molten material flowing through the passage in said part.

2. The structure defined in claim 1 wherein said part is formed of a material selected from the group consisting of tungsten carbide, titanium carbide and zirconium boride and a binder selected from the group consisting of cobalt and platinum.

3. In a pressure casting apparatus, a mold cavity, a pressure cylinder having a discharge opening for molten casting material communicating with the cavity and having an intake opening for molten casting material spaced inwardly from said discharge opening axially of said cylinder, a plunger movable in said pressure cylinder in an outward direction outwardly beyond said intake opening to inject molten casting material into said cavity and movable in an inward direction to a retracted position inwardly beyond the intake opening, means for closing said discharge opening upon initial inward movement of said plunger toward its retracted position to provide a vacuum in said pressure cylinder produced solely by the inward movement of said plunger and sufficient to draw molten casting material into said cylinder through said intake opening when the latter is uncovered by movement of said plunger to its retracted position, a con-

tainer for a supply of molten casting material supported below said pressure cylinder, a member projecting downwardly into said container below the level of the molten casting material in said container and having a vertically extending passage communicating at the lower end with said container below the level of the molten casting material and communicating at the upper end with said intake opening in said pressure cylinder to supply molten casting material to said pressure cylinder in response to the vacuum produced in said cylinder, said member being formed of a material selected from the group consisting of tungsten carbide, titanium carbide and zirconium boride and a binder selected from the group consisting of cobalt and platinum.

4. The structure defined in claim 3 comprising an annular seat on said pressure chamber surrounding said intake port, a part removably supported on said member at the top of the latter and having a passage therethrough establishing communication between the passage in said member and said intake port, an annular seat on said part surrounding the upper end of the passage through said part and engageable with the seat on said pressure chamber, the passage through said part having a cross sectional area predetermined to meter the molten material supplied to said pressure chamber, and said part being formed of the same material as said member.

5. In pressure casting apparatus, a mold cavity, a pressure chamber having a discharge opening for molten material communicating with the mold cavity and having an intake opening for molten material, means for introducing molten material into the pressure chamber through the intake opening including a part having a passage for molten material of a cross-sectional area predetermined to meter the flow of molten material admitted to the pressure chamber, said part being formed of a material selected from the group consisting of tungsten carbide, titanium carbide and zirconium boride and a binder selected from the group consisting of cobalt and platinum, pressure means for injecting the molten material admitted to the pressure chamber into the die cavity, said pressure chamber having an annular seating surface surrounding the intake opening at the outer side of the latter, and said part having an annular seating surface engageable with the seating surface on the pressure chamber, said seating surfaces having cross-sectional contours predetermined to provide a continuous line contact between the surfaces and thereby reduce heat transfer between said part and pressure chamber to a minimum.

6. The structure defined in claim 5, comprising a support for said part having a supply passage for molten material communicating with the passage in said part, and selectively operable means for moving the support together with said part into and out of operative relationship with respect to the pressure chamber.

7. The structure defined in claim 6 wherein the part is reversible end for end and is removably mounted on the support in either position thereof.

8. In pressure casting apparatus, a mold cavity, a pressure chamber having a discharge opening communicating with said mold cavity and having an intake opening, means for introducing molten casting material into said pressure chamber through said intake opening including a part having a passage for molten casting material of a cross-sectional area predetermined to meter the flow of casting material admitted to said pressure chamber, said part being formed of a material characterized in that it withstands the temperature of the molten casting material and is not affected by physical and chemical action of the casting material whereby the predetermined cross-sectional area of said passage is maintained for long periods of use, and means for expelling the casting material admitted to said chamber from said discharge opening, said chamber having an annular seating surface surrounding said intake opening at the outer side of the latter, and said part having an annular seating surface engageable

with the seating surface on said chamber, said part being formed of a sintered carbide material, and said seating surfaces having cross-sectional contours predetermined to provide a continuous line contact therebetween and thereby reduce heat transfer between said part and chamber to a minimum.

9. In pressure casting apparatus, a mold cavity, a pressure chamber having a discharge opening communicating with said mold cavity and having an intake opening, means for introducing molten casting material into said pressure chamber through said intake opening including a part having a passage for molten casting material of a cross-sectional area predetermined to meter the flow of casting material admitted to said pressure chamber, said part being formed of a material characterized in that it withstands the temperature of the molten casting material and is not affected by physical and chemical action of the casting material whereby the predetermined cross-sectional area of said passage is maintained for long periods of use, and means for expelling the casting material admitted to said chamber from said discharge opening, said chamber having an annular seating surface surrounding said intake opening at the outer side of the latter, and said part having an annular seating surface engageable with the seating surface on said chamber, said seating surfaces having cross-sectional contours predetermined to provide a continuous line contact therebetween and thereby reduce heat transfer between said part and said chamber to a minimum.

10. In pressure casting apparatus, a mold cavity, means for supplying molten casting material to said cavity including a pressure chamber having a discharge opening, said chamber also having an intake opening, means for introducing molten casting material into said pressure chamber through said intake opening including a part having a passage for molten casting material of a cross-sectional area predetermined to meter the flow of casting material admitted to said pressure chamber, means for expelling the casting material admitted to said chamber from said discharge opening, said chamber having an annular seating surface surrounding said intake opening at the outer side of the latter, and said part having an annular seating surface engageable with the seating surface on said chamber, said seating surfaces having cross-sectional contours predetermined to provide a continuous line contact therebetween and thereby reduce heat transfer between said part and said chamber to a minimum.

11. In a pressure casting apparatus, a mold cavity, means for delivering molten casting material to said mold cavity including a pressure cylinder having a discharge opening, a plunger supported in said cylinder for axial sliding movement in one direction toward said discharge opening to expel casting material in said cylinder from said discharge opening and in the opposite direction away from said discharge opening to a retracted position, said cylinder having an intake port between said discharge opening and said plunger in the retracted position of the latter, means for admitting molten casting material to said cylinder including a part having a supply passage communicating with said intake port and with a supply of molten casting material, and means for closing said discharge opening during movement of said plunger in said opposite direction to its retracted position to provide a vacuum in said cylinder at the side of said plunger toward said discharge opening produced solely by the movement of said plunger in said opposite direction and sufficient to draw molten casting material through said supply passage into said cylinder through said intake port, said passage being of a cross-sectional area predetermined to admit a metered amount of molten casting material to said cylinder in response to the vacuum produced therein by said plunger, and said part being formed of a material characterized in that it withstands the temperature of the molten casting

material without deterioration and is not affected by the physical and chemical action of the molten material flowing through the passage in said part.
